UNITED STATES PATENT OFFICE.

LEO S. BAUMAN, OF ST. LOUIS, MISSOURI, ASSIGNOR TO BAUMAN-MASSA JEWELRY COMPANY, OF ST. LOUIS, MISSOURI, A CORPORATION OF MISSOURI.

DESIGN FOR A FILLING TANK FOR CIGAR LIGHTERS.

Application filed February 23, 1928. Serial No. 25,542. Term of patent 14 years.

To all whom it may concern:

Be it known that I, LEO S. BAUMAN, a citizen of the United States, residing in the city of St. Louis, State of Missouri, have invented a certain new, original, and ornamental Design for Filling Tank for Cigar Lighters, of which the following is a specification, reference being had to the accompanying drawing, forming a part thereof, in which the figure illustrates in perspective a filling tank for cigar lighters embodying my new design.

I claim:

The ornamental design for a filling tank for cigar lighters substantially as shown.

LEO S. BAUMAN.
